BASTING SYRINGE

Morris Friedman, New York, N.Y., and Andrey V. Mackey, Ambler, Pa., assignors to Minerware, Inc., New York, N.Y., a corporation of New York and H.M.S. Associates Co., Willow Grove, Pa., a corporation of Pennsylvania, jointly

Filed Nov. 14, 1963, Ser. No. 77,416

Term of patent 14 years

(Cl. D44—29)

Fig. 1.

Fig. 4.

Fig. 3.

Fig. 2.

FIG. 1 is a side elevational view of a basting syringe showing our new design;

FIG. 2 is a top plan view of the bulb of the syringe; and

FIGS. 3 and 4 are respectively a front elevational view and a back elevational view of the bulb.

We claim:

The ornamental design for a basting syringe, substantially as shown.
